UNITED STATES PATENT OFFICE

HUGO BOHL, OF WESTFIELD, NEW JERSEY, ASSIGNOR TO RADIANT LIGHTING FIXTURE CO., INC., OF NEW YORK, N. Y.

DESIGN FOR A LIGHTING FIXTURE OR ARTICLE OF SIMILAR NATURE

Application filed February 12, 1930. Serial No. 34,497. Term of patent 3½ years.

To all whom it may concern:

Be it known that I, HUGO BOHL, a citizen of the United States, residing in Westfield, in the county of Union and State of New Jersey, have invented a new, original, and ornamental Design for a Lighting Fixture or Article of Similar Nature, of which the following is a specification, reference being had to the accompanying drawing, forming a part thereof.

Figure 1 is a perspective view of a lighting fixture showing my new design, in which the portions shown in plain outline involve mere

repeats of the portions shown completed in full lines.

Fig. 2 is a plan view of the bottom base plate thereof, in which the portions shown in plain outline involve mere repeats of the portions shown completed in full lines.

I claim:

The ornamental design for a lighting fixture, or article of similar nature, as shown and described.

In testimony whereof I affix my signature.

HUGO BOHL.
